UNITED STATES PATENT OFFICE.

JOHN H. KENNEDY, OF CLEVELAND, OHIO, ASSIGNOR TO JOSEPH P. FARNAN,
OF SAME PLACE.

STOP-COCK BOX FOR SERVICE-PIPES.

SPECIFICATION forming part of Letters Patent No. 363,649, dated May 24, 1887.

Application filed November 8, 1886. Serial No. 218,295. (No model.)

To all whom it may concern:

Be it known that I, JOHN H. KENNEDY, of Cleveland, in the county of Cuyahoga and State of Ohio, have invented certain new and 5 useful Improvements in Stop-Cock Boxes for Service-Pipes; and I do hereby declare the following to be a full, clear, and exact description of the invention, such as will enable others skilled in the art to which it pertains 10 to make and use the same.

My invention relates to improvements in stop-cock boxes for service-pipes, in which is employed an extensible cap of considerable length, that may be adjusted lengthwise of the 15 box to bring the cap flush with the pavement. A locking device is provided to temporarily hold the cap at the desired elevation while the box is being set, with the arrangement of parts such that after the filling is tamped around 20 the cap the locking device can be unlocked and the cap left supported by the filling, to the end that in case the ground is upheaved by the frost only the cap is moved and the body of the box is not disturbed. A detachable base is provided, the same having an upwardly-projecting annular rim made to overlap the box and turn or slide easily thereon. The rim internally has spiral grooves and the 25 box has projecting lugs for engaging the grooves, to the end that by turning the base in one direction it is drawn upward and made to clamp the ends of the cock, the latter extending out through slots in the body of the box, such clamping device being adapted to 30 receive cocks of different sizes.

In the accompanying drawings, Figure 1 is a side elevation of a stop-cock box embodying my invention, portions being broken away to show the construction. Fig. 2 is an elevation 40 in section taken at right angles to the view shown in Fig. 1.

A represents the body of the box, the same consisting, essentially, of an upright hollow open-ended metal column.

45 B is a removable base, and C an extension-cap. The base has an upwardly-projecting annular rim, B', made to fit over the lower end of the box A and to slide or turn easily thereon. The rim B', internally and on opposite 50 sides thereof, is provided with grooves b, the

same extending from the top edge of the rim downward a short distance, and then circumferentially, but inclining downward, as shown.

The box A, near the bottom, has outwardly-projecting lugs or pins a, that operate, respectively, in the grooves b, by reason of which, when the parts are in position, by turning the base in one direction the base is drawn upward on the box.

D is a stop-cock, the body of which is located inside the box, with the ends thereof, d, to which the service-pipe is to be attached, extending out through notches a', made in the lower edge of the box. By turning the base as aforesaid, the latter is brought up in contact with the projecting ends d, bringing the latter into the notches a' and clamping them, in which position the cock is ready for attaching the service-pipe.

As the notches a' are triangular on top, the 60 lines diverging abruptly, two or three sizes of the cock may be secured, respectively, in the clamp. The cap C is of considerable length, and fits easily over the top of the box. A lug, a², projects from the box and operates in 65 a vertical groove, c, made on the inside of the cap. This groove is in open relation with a series of notches, c', made along the one side of the groove, the notches being respectively adapted to receive the lug a². The groove at 70 the bottom has a lateral extension, c'', from the end of which latter the groove c'' extends to the lower edge of the cap, the lateral portion of the groove serving as a stop to prevent the cap from being inadvertently pulled off 75 the box in handling. The cock is operated by means of a detachable square rod, E, the latter being made of suitable length to extend well up into the cap, where it is easily reached with a socket-wrench, the head of the cap having 80 an opening for the purpose, said opening being closed by a screw-plug, F. The latter has preferably a triangular-shaped head, f, made flush with the head of the cap, so that it is out of the way and cannot be turned by 85 an ordinary wrench. The parts being assembled, the box is set in the ground and the service-pipe connected. The cap is raised or lowered to bring the top thereof to the desired 90 elevation flush with the pavement, and is se- 95

100

cured temporarily by turning the cap to bring the lug a^2 into one of the notches c' . The filling, after it is packed, will support the cap, and the latter is then turned to disengage the 5 lug a^2 from the notch c' , bringing the lug into the vertical notch c , in which position of parts, if the ground freezes to the cap and is upheaved by the frost, the cap may move vertically with the ground without disturbing the 10 box A, and in such cases the pavement and cap will usually retain their relative positions. The box, base, and cap are usually of cast-iron.

What I claim is—

15 1. As a new article of manufacture, a stop-cock box for service-pipes, consisting, essentially, of a body, cap, and base, the body and cap being provided with devices for temporarily locking them together while the box is 20 being placed in position, and the base adapted

to overlap and fit loosely on the box and provided with inclined grooves adapted to engage projecting lugs on the box, substantially as and for the purpose set forth.

2. In a stop-cock box for service-pipes, the 25 combination, with the body of the box, of a detachable base, the latter being made to overlap and fit loosely on the box, the base having inclined grooves and the box having projecting lugs for engaging the grooves, the parts 30 being arranged substantially as indicated, for clamping the cock between the base and box, substantially as set forth.

In testimony whereof I sign this specification, in the presence of two witnesses, this 5th 35 day of October, 1886.

JOHN H. KENNEDY.
